(57) **CLAIM**

The ornamental design for a retaining wall block, as shown and described.

DESCRIPTION

FIG. 1 is a perspective view of a retaining wall block showing our new design;

FIG. 2 is a left side elevational view thereof, the right side elevational view being a mirror copy of this view;

FIG. 3 is a top plan view thereof;

FIG. 4 is a front elevational view thereof;

FIG. 5 is a rear elevational view thereof; and,

FIG. 6 is a front perspective view thereof, in an exploded form.
